UNITED STATES PATENT OFFICE.

EMILE C. REUTLINGER, OF BOSTON, MASSACHUSETTS.

WATER-MOTOR.

1,382,237.

Specification of Letters Patent. Patented June 21, 1921.

Application filed June 11, 1919. Serial No. 303,297.

To all whom it may concern:

Be it known that I, EMILE C. REUTLINGER, a citizen of Switzerland, and resident of Boston, county of Suffolk, State of Massachusetts, have invented an Improvement in Water-Motors, of which the following description, in connection with the accompanying drawing, is a specification, like characters on the drawing representing like parts.

10 This invention relates to improvements in fluid motors and the principal object thereof is to provide a motor of this character of simple construction which can be easily and economically manufactured and which will be efficient in operation.

15 A further object of the invention is to provide a motor of the character above described which can be easily assembled and dismantled by persons who are not machinists so that worn or damaged parts may be readily replaced.

20 A further object of the invention is to provide a novel form of valve chamber which can be readily assembled and dismantled.

25 A further object of the invention is to provide a fluid motor having cylinders which are formed of relatively thin metal walls enclosed in and supported by the rigid walls of a casting.

30 A further feature of the invention consists in providing cylinders of the type above described with hollow heads attached to conduits through which the fluid under pressure may be introduced.

35 A further object of the invention is to provide a motor of the character above described with a base in the form of a bracket which may be attached to a vertical ledge such as the wall of a washing machine or

40 to any convenient support.

45 Other objects and features of the invention will more fully appear from the following description and the accompanying drawings and will be pointed out in the annexed claims.

50 The invention is disclosed herein as adapted for operating the plunger of a washing machine but it will be understood that it is not limited to such use and may be employed wherever convenient and desirable.

In the drawings:

Figure 1 is a side elevation of a motor embodying my invention applied to the plunger or dasher of a washing machine,

55 Fig. 2 is a vertical longitudinal section

through the cylinders of the motor and its supporting base or bracket,

Fig. 3 is a side view showing the valve chamber and valves in vertical section,

Fig. 4 is a vertical transverse sectional view on line 4—4 Fig. 2, and

Fig. 5 is a detail view of the chambered cylinder head.

The motor is illustrated in the accompanying drawings as supported upon a bracket comprising a base 1 having a shoulder 2 adapted to engage a suitable vertical support 3 and a member 4 extending in parallelism therewith having a thumb or hand screw 5 passing through it provided at its end with a block 6 adapted to clamp upon the opposite side of the support 3. The base 1 is provided with upwardly extending integral bosses 7 and 8 which are cored out to form aligned cylindrical apertures 9 and 10 adapted to receive the motor cylinders 11 and 12. The cylinders 11 and 12 may be formed of suitable tube material smoothly bored to receive the pistons. These cylinders may be and preferably are removably secured in the bosses and are provided with chambered heads 13 and 14 which may be in the form of hollow castings having flanges 15 and 16 embracing the remote ends of the cylinders, screwed, welded or preferably sweated upon them.

The piston heads may be formed in any desirable manner. As shown herein they each comprise cylindrical members 17 and 18 inclosing a packing or ring 19 which may be made of fibrous material and are clamped together by bolts 20. The pistons desirably are secured together by rods 21 preferably three in number spaced one hundred and twenty degrees apart. A link 22 which may be connected to one of said cylinder heads is connected at its opposite end to a member 23 of a power actuating lever 24 the end of which is bifurcated and provided with pivot screws 25, 26 which engage sockets 100 in an overhanging bracket 28 which desirably is formed integral with the boss 7 on the base 1.

Fluid under pressure is supplied to the cylinders through a valve chamber which for convenience in manufacture and assembling is formed of three members, an inner member providing a compartment having inlet and exhaust sections, the outer members communicating through suitable ports with said 110

sections and also with the hollow heads 13, 14 of the cylinders. As illustrated herein the central member 29 of the valve chamber comprises a casting which has an ex- 5 tension or bracket secured to the base 1 and which is provided with an inlet port 30 and an outlet port 31. The outer members 32 and 33 are in the form of elongated cham- 10 bers having at their upper ends extensions 34 and 35 which are respectively connected by pipes 36, 37 with lateral hollow exten- 15 sions 39 and 40 upon the heads 14 and 13 respectively.

The members of the valve chamber may 15 be and are connected by bolts 41 which serve to clamp the members of the casing together.

Partitions 42, 43, 44 and 45 are interposed between the adjacent ends of the outer mem- 20 bers of the valve casing and the inner mem- 25 ber and these partitions are provided with ports leading from the inlet and outlet sec- tions of the inner member to the outer cham- bers. A valve 46 located in the inlet section 30 of the inlet chamber is adapted to seat alter- 35 natively upon the ports 44 and 45 to control the flow of fluid under pressure to the cylinders 11 and 12. This valve desirably is carried by aligned rods 47, 48 which are connected at their respective outer ends to levers 49 and 50 located in the outer chambers of 35 the valve casing and pivotally mounted upon studs 51 and 52 extending across the walls of said chamber. The ports of the partitions 42 and 43 are alternatively opened 40 and closed by valves 53 and 54 carried by a link 55 which is pivotally connected at its ends to studs 56 and 57 in the ends of the levers 49 and 50, respectively.

The link 55 is provided intermediate of its 45 end and within the exhaust chamber of the inner member of the valve casing with an aperture 58 which receives the end of an arm 59 carried upon a shaft 60 which is jour- 50 naled in the walls of an upward extension 55 61 of the inner valve casing member. A rocker 62 which is secured to the shaft 60 is adapted to be operated by the movement of the power transmitting lever 34 in such a manner as to reciprocate the link 55 and thereby alternately close the ports in the 55 partitions 42 and 43 and simultaneously to cause the reverse operation of the valve 46 which controls the ports leading from the inlet section of the inner member of the valve casing.

Any suitable means may be provided for actuating the rocker 62. As disclosed herein the member 23 of the power transmitting lever is in the form of a flat web 63 which 60 has projecting from it a guide 64 having a central aperture 65. The rocker is provided at or adjacent its ends with rollers 66, 67 which are mounted upon laterally projecting studs so that the rollers engage the guide 65 64. The guide 64 is in the form of an arc

concentric with the center of the stud 25 about which the power transmitting lever operates.

Means are provided for depressing alter- 70 nately the ends of the rocker 62 so that the rollers 66 will alternately engage the under- 75 side of the guide 64. The preferred means illustrated in the accompanying drawing for accomplishing this purpose comprises a bell 80 crank lever pivotally mounted upon a stud 75 85 68 upon the web 63 of the power transmitting lever and having an arm 69 provided at its outer end with a roller 70 which rests upon and rides over the upper surface of the rocker 62. The opposite arm 71 of said bell crank lever is connected to a helical 85 spring 72 which is anchored at its opposite end in an eye bolt 73 passing through a lug 74 extending upwardly from and preferably integral with the web 63 of the power trans- 90 mitting lever.

The power transmitting arm 24 may be connected to any suitable device which is to be reciprocated. As illustrated the outer end of the arm 24 is connected to the stand- 95 ard 75 of the dasher 76 of the washing machine having the standard 75 connected by a link 77 which extends in parallelism with the power transmitting member 24 and is pivotally connected at its opposite end to a 95 stud 78 upon the base 1.

In the operation of the machine fluid under pressure, such as water, introduced 100 through the inlet port 30, flows through the inlet chamber 29 of the valve casing, the pipe 36 and hollow head 14 into the cylinder. When this cylinder has been driven to the limit of its stroke as is illustrated in 105 the accompanying drawings the roller 66 in the end of the rocker arm 62 is brought directly above the aperture 65 in the guide 64 and is depressed through said aperture by the force of the spring 72 acting through 110 the bell crank lever arms 71 and 69 and roller 70. This rocks the arm 59 from the position illustrated in Fig. 3 so that the valve 46 closes the port in the partition 44 and simultaneously therewith opens the port in the partition 45, thus establishing com- 115 munication with the opposite cylinder 11. At the same time the valve 54 is unseated from the port in the partition 42, thus permitting the fluid to exhaust from the cylinder 14 through the chamber 32, the port in 120 the partition 42 and the exhaust port 31 so that as the fluid under pressure is supplied to cylinder 11 it will be simultaneously exhausted from the cylinder 12.

This will cause reciprocation of the pis- 125 tons in the opposite direction, raising the power transmitting lever 24. Inasmuch as the web 63 is carried by the lever 24 the guide 64 will move toward the left Fig. 2 until the aperture 65 comes beneath the roller 67 on the rocker 62. In the meantime 130

the roller 70 will have been carried over the upper surface of said rocker and will be in position to depress the roller 67 through the aperture 65 when the latter comes beneath said roller. This will shift the rocker in the opposite direction, thus moving the arm 59 back to the position illustrated in Fig. 3 and thereby opening the exhaust port for the cylinder 11 in the partition 43 and simultaneously opening the supply port for the cylinder 12 in the partition 44.

The construction above described, it will be noted, is of a simple character which can easily and economically be constructed.

15 The base, cylinder holders, and overhanging arm 28 may be cast in one piece of relatively cheap material. The cylinders 11 and 12 may be made of high grade material and when sweated or otherwise secured within 20 the cylinder holders will provide efficient and lasting cylinders for the machine. The cylinder heads can be readily constructed by casting and sweated upon the ends of the cylinder.

25 The piston construction is of an inexpensive character and when the parts thereof are assembled and connected together by the rods 21 a rigid piston structure is provided. The valve operating mechanism is simple in 30 character and the valve chambers are so constructed that they can be readily removed and replaced.

By reason of this fact the partitions 42, 43, 44 and 45 which contain the ports between the inner and outer valve chambers, 35 may be made of rubber or fibrous material and readily replaced by the user of the machine when they become worn without the necessity of returning the machine to the 40 factory.

It will be understood that the embodiment 45 of the invention disclosed herein is of an illustrative character and is not restrictive and that various changes in construction and parts may be made within the spirit and scope of the claims and that the motor forming the subject matter of my invention may be adapted for various uses.

Having thus described my invention what 50 I claim as new and desire to secure by Letters Patent is:

1. A fluid motor comprising a base having means adapted to be secured to a support and bosses integral therewith spaced apart 55 and provided with aligned cylindrical apertures, cylinders secured in said apertures, connected pistons in said cylinders, chambered heads secured to said cylinders, inlet and outlet conduits connected to said chambered heads, a valve chamber connected to 60 said conduit, valves in said chamber for controlling communication to said cylinder heads, a bracket on one of said bosses overhanging the space between said bosses, a power transmitting arm pivotally mounted

on said bracket, valve operating mechanism connected to said arm, and means connecting one of said pistons to said valve operating mechanism.

2. A fluid motor comprising a base, a pair 70 of aligned cylinders carried thereby and having connected pistons, a bracket on said base, a power transmitting arm pivotally connected to said bracket and to one of said pistons and means for supplying fluid under pressure alternately to said cylinders.

3. A fluid motor comprising a base, a pair 80 of aligned cylinders carried thereby and having connected pistons, a bracket on said base, a power transmitting arm pivotally connected to said bracket having a member connected to one of said pistons and valve controlling mechanism carried by said member.

4. A fluid motor comprising a base having 85 a pair of aligned cylinders spaced apart, chambered heads connecting with the ends of said cylinders, a valve chamber having inlet and outlet ports communicating with said heads, a valve in said valve chamber, a rocker for operating said valve, a bracket 90 carried by said base, a power transmitting lever pivoted to said bracket, and means carried by said power transmitting lever for actuating said rocker.

5. A fluid motor comprising a base having 95 a pair of aligned cylinders spaced apart, chambered heads connecting with the ends of said cylinders, a valve chamber having inlet and outlet ports communicating with said heads, a valve in said valve chamber, 100 a rocker for operating said valve, a bracket carried by said base, a power transmitting lever pivoted to said bracket, means carried by said power transmitting lever for actuating said rocker comprising a guide adapted 105 to engage the ends of said rocker and a spring actuated instrumentality operable upon reciprocation of said lever to present the opposite ends of said rocker alternately to said guide.

6. A fluid motor comprising a piston and cylinder, a power transmitting lever and means connecting said power transmitting lever to said piston, means for supplying fluid under pressure to said cylinder including inlet and exhaust valves, a rocker connected to said valves, a guide on said power transmitting lever and means carried by said lever acting to present the ends of said rocker alternately to said guide.

7. A fluid motor comprising a piston and cylinder, a power transmitting lever and means connecting said power transmitting lever to said piston, means for supplying fluid under pressure to said cylinder including inlet and exhaust valves, a rocker connected to said valves, a guide on said power transmitting lever, a spring actuated member carried by said power transmitting lever having means engaging said rocker and 130

operating to present alternately the opposite ends of said rocker to said guide.

8. A fluid motor comprising a piston and cylinder, a power transmitting lever and means connecting said power transmitting lever to said piston, means for supplying fluid under pressure to said cylinder including inlet and exhaust valves, a rocker connected to said valves having a roller at each 10 of its ends, a guide upon said power transmitting lever and a spring actuated lever carried by said power transmitting lever having a roller engaging said rocker and operating to present its ends alternately to 15 said guide.

9. A fluid motor comprising a pair of cylinders spaced apart, chambered heads secured to said cylinders, means for supplying fluid under pressure to said cylinder heads including a valve chamber comprising outer valve compartments communicating with said heads and an inner valve compartment located between said outer valve compartments having inlet and outlet sections,

partition walls clamped between said compartments having ports connecting said outer valve compartments with the sections of said inner compartment, valves for said ports and means for actuating said valves. 25

10. A fluid motor comprising a cylinder, 30 means for supplying fluid under pressure to said cylinder including a valve chamber consisting of an inner compartment having inlet and outlet sections and outer compartments having means communicating with 35 said cylinder, means for detachably clamping the sections of said valve chamber together, partition walls between said sections having valve seats provided with ports leading from the outer compartments to the respective sections of the inner compartments, valves for said ports and means operable by the movement of said pistons for actuating said valves. 40

In testimony whereof, I have signed my 45 name to this specification.

EMILE C. REUTLINGER.
